ATTORNEY

UNITED STATES PATENT OFFICE.

HERMAN SCHLIRF, OF MILWAUKIE, OREGON.

FLAG GAME.

1,253,891.

Specification of Letters Patent. Patented Jan. 15, 1918.

Application filed July 9, 1917. Serial No. 179,454.

To all whom it may concern:

Be it known that I, HERMAN SCHLIRF, a citizen of the United States, residing at Milwaukie, in the county of Clackamas and 5 State of Oregon, have invented new and useful Improvements in Flag Games, of which the following is a specification.

This invention relates to games and the object in view is to provide a game embodying in connection with a stationary support, board or field, a plurality of movable members or blocks of special formation adapted to be moved or shifted from place to place and arranged in vertical and 10 horizontal rows, there being a sufficient number of such movable members to entirely cover the field excepting only a space equal to that ordinarily occupied by a single block, and the game as a whole being of a highly educational character as well as 15 entertaining both to adults and children.

With the above and other objects in view, the invention consists in the novel construction, combination and arrangement of 20 parts, herein fully described, illustrated and claimed.

In the accompanying drawings:—

Figure 1 is a plan view of the game apparatus omitting the movable members of 25 blocks.

Fig. 2 is also a plan view, showing the movable members or blocks in their final positions.

Fig. 3 is a vertical sectional view on the 30 line 3—3 of Fig. 2.

The game apparatus contemplated in this invention, comprises a board or support having a field 1 and a surrounding flange or frame 2. One side 3 of the frame is of 35 considerably greater width than the remaining three sides, the frame as a whole being rectangular in shape, the wider or broader side 3 having printed or otherwise represented thereon the names of the foreign countries now engaged in the world's war, said names being abbreviated as shown at 4.

The field 1 is blocked off by intersecting lines 5 and 6 extending at right angles to 40 each other to provide a plurality of spaces arranged in vertical and horizontal rows and each of said spaces has printed or otherwise represented thereon the name of one of the belligerent countries. All of the 45 spaces in each horizontal row have the name of the same country represented thereon as

shown in the drawings and such name is preferably printed in full in order that the persons playing the game may become familiar with the proper spelling of the foreign countries. At the same time persons 60 become familiar with the abbreviations in the spelling of the names of said countries.

In conjunction with the support or board hereinabove described, I employ a number 65 of movable members or blocks 7, there being as many blocks as there are spaces between the intersecting lines 5 and 6, less one, one vacant space being left in order to permit the movable members or blocks to 70 be shifted about until they are arranged in the same manner as the printed names of the countries on the individual spaces on the field. Each of the blocks or movable members is rectangular in plan, being of greater 75 dimensions in one direction than in the other. The top of each block is rounded or arched as shown for the purpose of enabling the blocks to be quickly manipulated as it will be seen that the fingers may be readily 80 placed upon opposite sides of any block to be shifted without interfering with other blocks adjacent thereto. Furthermore such rounded formation of the top of each block 85 enables a good grip to be obtained on the block preparatory to shifting the same from one place to another.

Each block carries on its rounded face the flag or colors of the country which it represents. Such rounded surface of the block 90 also has imprinted or otherwise represented thereon the name of the respective country followed by the area in square miles of said country and the total population of said country. This makes the game as a 95 whole very instructive as well as entertaining as persons playing the game become perfectly familiar with the flags and colors of all the countries involved in the world's war together with the number of citizens or 100 subjects of such countries and the area in square miles, as well as proper spelling of said countries and the proper abbreviations for the spelling of the names of said countries.

In playing the game the movable members or blocks are placed indiscriminately upon the field and the player or players then move the blocks one at a time with the object of disposing the blocks of each country 110 in the row designated on the field or in other words until all of the spaces design-

nated by the names of any particular country are occupied by the blocks or movable members appropriated to said country.

In the drawings there are 9 rows of 5 spaces, 3 spaces in each row but such number is merely illustrative of the invention, it being apparent that the number of rows will correspond with the number of countries at war and the number of spaces in 10 each row may be varied to suit the manufacturer.

I claim:—

In a game apparatus, a support embodying a rectangular field, a marginal frame 15 extending around said field and also of rectangular formation, one side of said frame being broader than the other three sides and having represented thereon in column

formation the names of various countries abbreviated, the field being divided by intersecting lines extending at right angles to each other into individual spaces having represented thereon the names of the various countries printed in full, each horizontal row of individual spaces being appropriated to the same country, and shiftable blocks of the same number as the individual spaces of the field less one, each block having an arched top surface upon which is represented the flag of one of the 30 countries together with the name of such country, the area in square miles and the total population.

In testimony whereof I affix my signature.

HERMAN SCHLIRF.

Copies of this patent may be obtained for five cents each, by addressing the "Commissioner of Patents, Washington, D. C."
